US0D1029026S

(12) **United States Design Patent** (10) Patent No.: US D1,029,026 S
Mairs et al. (45) Date of Patent: ** May 28, 2024

- (54) **DISPLAY SCREEN OR PORTION THEREOF WITH A GRAPHICAL USER INTERFACE**

(71) Applicant: **INSPIRE MEDICAL SYSTEMS, INC.**, Golden Valley, MN (US)

(72) Inventors: **Nicholas Mairs**, Minneapolis, MN (US); **Kent Lee**, Minneapolis, MN (US); **Brody Belland**, St. Louis Park, MN (US)

(73) Assignee: **INSPIRE MEDICAL SYSTEMS, INC.**, Golden Valley, MN (US)

(**) Term: **15 Years**

(**) Term: **15 Years**

(21) Appl. No.: 29/817,651

(22) Filed: Dec. 2, 2021

(51) LOC (14) Cl. 14-04

(52) U.S. Cl.

USPC D14/486

(58) **Field of Classification Search**

CLAIM

The ornamental design for a display screen or portion thereof with a graphical user interface, as shown and described.

DESCRIPTION

The FIGURE is a front view of a display screen or portion thereof with a graphical user interface showing our new design.

In the FIGURE, the outermost broken lines show a display screen or portion thereof and form no part of the claimed design. The remaining broken lines show elements of the graphical user interface that form no part of the claimed design.

1 Claim, 1 Drawing Sheet
